UNITED STATES PATENT OFFICE.

FRANK ZWICK, OF QUINCY, ILLINOIS.

DESIGN FOR AN ILLUMINATED SIGN.

Application filed June 22, 1922. Serial No. 2,780. Term of patent 14 years.

To all whom it may concern:

Be it known that I, FRANK ZWICK, a citizen of the United States, residing at Quincy, in the county of Adams and State of Illinois, have invented a new, original, and ornamental Design for an Illuminated Sign, of which the following is a specification.

Referring to the drawing:—

The figure of the drawing is an elevation of my illuminated sign, showing my new design.

I claim:—

The ornamental design for an illuminated sign, substantially as shown.

In testimony that I claim the foregoing as my own, I have hereto affixed my signature.

FRANK ZWICK.
